UNITED STATES PATENT OFFICE.

AUSTIN A. RILEY, OF INDIANAPOLIS, INDIANA, ASSIGNOR OF TWO-THIRDS TO CENTRAL STATES BRIDGE COMPANY, OF INDIANAPOLIS, INDIANA, A CORPORATION OF INDIANA.

OIL BURNER.

1,423,032.

Specification of Letters Patent. Patented July 18, 1922.

Application filed May 16, 1921. Serial No. 469,755.

To all whom it may concern:

Be it known that I, AUSTIN A. RILEY, a citizen of the United States, residing at Indianapolis, in the county of Marion and State 5 of Indiana, have invented new and useful Improvements in Oil Burners, of which the following is a specification.

The object of this invention is to provide an oil burner in which air to effect complete 10 combustion is provided in quantities regulated to suit the supply of oil, and in a manner to thoroughly nebulize the oil in a chamber provided within the nozzle, before discharge for ignition.

15 A further object is to simplify and cheapen the cost of construction, installation and maintenance of devices of this character, making same more durable and effective generally than devices of this character.

20 I accomplish the above, and other objects which will be hereinafter disclosed, by the mechanism illustrated in the accompanying drawing, in which:—

25 Figure 1, is a longitudinal vertical section of my invention detached from its appurtenances and in its simplest form, on the line 1—1, of Fig. 2, and Fig. 2 is a cross section of same on the line 2—2 of Fig. 1.

30 The body 3, and nozzle 4, are preferably one integral casting, with a chamber 5 and ample air-opening 6 thereto. The nozzle contains an atomizing chamber 7 having a reduced funnel-shaped discharge opening 8. The other side of the chamber 7 is open full 35 to the chamber 5, subject to regulated closure by a valve 9, which is adapted to be seated in a valve-seat 10 formed at the junction of chambers 5 and 7, and to be removed therefrom in proportion to the size of valve-opening desired at any time.

40 The side of chamber 5 has a cylindrical opening which is normally closed by a plug 11, which makes a gas-tight fit therein, aided by a flange 12 on the outer end of the plug. 45 The plug is retained by a set screw 13. The plug 11 is provided with a central screw-threaded opening to receive the threaded portion of the stem 15 of valve 9, and mounted on the end of the stem, outside of the plug, is a hand-wheel 14 by which the stem is screwed in and out through the plug 11 to regulate the distance of the valve away from its seat, or in other words, to regulate the size of the valve opening. A lock-nut 16

holds the wheel on the valve-stem. The 55 valve-stem 15 is hollow and the bore extends through the valve in the manner shown. Making a close sliding fit in said bore is a pipe 17, to the outer threaded end of which connection is made with a source of supply 60 of fuel oil (not shown). The inner end of this pipe terminates at the end of the valve when the valve is in its closed or seated position shown in the drawing. It discharges into a nozzle 20 having a reduced bore terminating with the nozzle near the outlet from nozzle 4. The opposite end of nozzle 20 makes a close sliding fit in the adjacent end of the gas pipe 17, and the wall of the nozzle 20 is thickened on its outside to form 70 a shoulder against pipe 17 and also to provide suitable thickness of metal for the seats of set screws 22. The latter are four in number, equidistantly placed around nozzle 4, through threaded holes in which the set 75 screws are adjusted to center the oil tip or nozzle 20. The nozzle 20 supports and centers the pipe 17, which pipe is the guide for the valve 9.

80 The operation of my invention is as follows: The device is installed with the nozzle 4 entering and discharging into the fire-box of the furnace and with pipe 17 connected with an oil supply. With the screws 22 loose to give free movement to nozzle 20, the 85 valve 9 is firmly seated in seat 10 by turning hand wheel 14, and then the four set screws 22 are each screwed in firmly against the oil tip or nozzle 20, to hold the latter against further displacement. The nozzle 20 then 90 serves to center the pipe 17, which pipe 17 is the guide for the valve 9. Oil is supplied under pressure through pipe 17, controlled by the usual cut-off valve in the pipe (not shown), and the air-valve 9 is adjusted by 95 turning the hand-wheel 14 to admit just the right amount of air to the nozzle 4 to thoroughly nebulize the oil supplied through oil tip 20, and to properly mix with the hydro-carbon element for the thorough combustion 100 of the latter.

Having thus fully described my invention, what I claim as new and wish to secure by Letters Patent of the United States is:—

1. The combination, in an oil burner, of 105 a hollow body-portion having an air inlet, a nozzle extending from the body, a valve-seat at the junction of the nozzle and body,

- an oil supply pipe entering the body opposite the nozzle, an oil-tip nozzle in the first nozzle, means for centering it with the valve-seat, said oil-tip nozzle supporting the oil-supply pipe centrally of the valve-seat, a valve cooperating with the valve-seat, said valve having a stem and the stem and valve having an opening by which they are slidably mounted on the oil-supply pipe.
- 10 2. The combination, in an oil burner, of a hollow body-portion having an air inlet, a nozzle extending at an angle from the body, a valve-seat at the junction of the nozzle with the body, an opening into the hollow 15 interior of the body opposite the nozzle, a plug normally closing said opening, said plug having a central hole, an oil-supply pipe entering the body through the hole in the plug, an oil-tip nozzle in the first nozzle 20 supporting the inner end of the oil-supply pipe, adjustable means for supporting the oil-tip nozzle centrally of the valve-seat, a valve and stem having a longitudinal opening by means of which they are slidably 25 mounted on the oil-supply pipe so the valve will cooperate with the valve-seat, the stem of the valve extending outside of the body-member through the hole in the plug, and said stem having threads screwing into 30 threads in the hole of the plug as means for adjusting the valve relative to the valve-seat by rotating the valve-stem, and manually operated means for rotating the valve stem.
- 35 3. The combination, in an oil burner, of a hollow body-portion having an air inlet, a nozzle extending at an angle from the body, said nozzle having a mixing chamber with a reduced outlet, a valve-seat at the junction 40 of the mixing chamber with the hollow interior of the body, said body having an opening diametrically opposite the nozzle, a plug normally closing the last opening said plug having a screw-threaded central hole,
- an oil-tip nozzle in the mixing chamber of 45 the first nozzle, a plurality of set screws entering the nozzle radially and supporting the oil-tip nozzle and providing means for centering the latter relative to the valve-seat and the reduced outlet of the first nozzle, an oil-supply pipe of considerably less 50 diameter than the hole in the plug passing loosely through said hole and supported at its inner end on the oil-tip nozzle, a valve and valve-stem having a longitudinal opening 55 through them by which they are mounted with a sliding fit on the oil-supply pipe, the valve-stem having screw-threads engaging with the threads of the plug, and manually operated means on the outer end of the stem 60 to rotate the stem and valve to regulate the position of the valve with relation to its seat.
4. The combination, with a valve-body having an air-inlet, a valve-seat and a nozzle outlet, of an oil-supply pipe entering the body, said nozzle supporting the oil-supply pipe centrally of the valve seat, means for centering the nozzle with the valve seat, a valve slidably mounted on the oil-supply 70 pipe, and means extending outside of the body for adjusting the valve in its seat.
5. The combination, with a valve-body having an air-inlet, a valve-seat and a nozzle outlet, of an oil-supply pipe entering the 75 body, said nozzle supporting the oil-supply pipe centrally of the valve seat, means for centering the nozzle with the valve seat, means extending outside of the body for centering the inner end of the pipe, a valve 80 slidably mounted upon the oil supply pipe, and means extending outside of the body for adjusting the valve toward and from its seat to regulate the supply of air to the oil.

Signed at Indianapolis, Indiana, this 29th day of April, 1921.

AUSTIN A. RILEY
